The ornamental design for a flashlight head, as shown and described.

DESCRIPTION

FIG. 1 is a front perspective view of a flashlight head showing our new design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a rear view thereof.

The broken lines on the flashlight head, the remaining flashlight body and tail cap represent unclaimed portions and form no part of the claimed design. The broken line adjacent to the rear of the shaded region represents an unclaimed boundary of the design.
